CONVERTIBLE SEAT OR SIMILAR ARTICLE OF FURNITURE

Frank W. Petersilie, Boone, N.C., assignor to Investments & Innovative Concepts, Inc., Boone, N.C.

Filed Aug. 29, 1974, Ser. No. 501,626

Term of patent 14 years

Int. Cl. D6—01

U.S. Cl. D6—64

FIG. 1 is a front perspective view of a convertible seat showing my new design;

FIG. 2 is a top plan view of FIG. 1;

FIG. 3 is a front perspective view of the convertible seat of FIG. 1 being partially folded over for converting into a bed or similar article;

FIG. 4 is a perspective view of the convertible seat converted into a bed or similar article;

FIG. 5 is a top plan view of FIG. 4;

FIG. 6 is a front perspective view similar to FIG. 1 with the ottoman inverted and repositioned;

FIG. 7 is a top plan view of FIG. 6;

FIG. 8 is a front perspective view of the convertible seat of FIG. 1 with the ottoman omitted;

FIG. 9 is a top plan view of FIG. 8; and

FIG. 10 is a rear perspective view of FIG. 8.

I claim:

The ornamental design for a convertible seat or similar article of furniture, substantially as shown.
